UNITED STATES PATENT OFFICE.

JAMES F. WILLSON, OF DEUEL, COLORADO, ASSIGNOR OF TWO-THIRDS
TO I. G. AKER AND FRANK W. BUCKLEY, OF DEUEL, COLORADO.

BEET-TOPPER.

No. 824,051.

Specification of Letters Patent.

Patented June 19, 1906.

Application filed June 24, 1905. Serial No. 266,826.

To all whom it may concern:

Be it known that I, JAMES F. WILLSON, a citizen of the United States, residing at Deuel, in the county of Morgan and State of Colorado, have invented certain new and useful Improvements in Beet-Toppers, of which the following is a specification.

My invention relates to beet-toppers, and has for its object to provide a device adapted to be attached to the frame of a beet-puller, which will cut off the tops of the beets just before they are engaged by the pulling mechanism.

A further object of my invention is to provide a device adapted to cut off as much of the crown as desired, this being accomplished in a satisfactory manner by providing knives other than the crown-cutting knives for cutting and removing the leaves.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a top plan view of my improved beet-topper. Fig. 2 is a side elevation. Fig. 3 is a front elevation. Fig. 4 is a modification of the vertical knife.

Referring to the drawings, in which like numerals of reference indicate corresponding parts throughout the several views, 1 is a weighted gage-block provided with a vertical slot 2, extending longitudinally therethrough.

The topper-knives comprise a vertical knife 3, adjustably secured within the slot 2 by bolts 4. Formed integral with said vertical knife and at right angles thereto are two knives 5 and 6. The cutting edges of these knives when taken together are substantially semicircular, the backs of the knives being at or near the rear of the vertical knife 3. In recesses 7 and 8 in the gage-block are secured two knives 9 and 10, the cutting edges of said knives being horizontal and on a line with the bottom of the gage-block. The rearward portion of knives 9 and 10 is twisted outward, so as to throw the severed leaves away from

the beet. In order that the several knives above described may be able to perform their work without being unnecessarily hampered by the overhanging leaves of the beets, I provide cutting-disks 11 and 12, which travel ahead of the gage-block 1 and sever the leaves which hang on either side of the row. These disks are carried by shaft 13, which is slidably mounted on projection 14 of the gage-block 1. The disks 11 and 12 are adapted to be set at an angle to the row, so that the leaves after being cut will be thrown away from the knives which follow.

The topper is pivotally secured by projection 14 to the frame of a beet-puller in line with the pulling mechanism. The topper is held in alignment with the pulling means by springs 15 and 16, the ends of which are secured to the sides of said frame and to a rod 18, carried by the gage-block. It being necessary to increase the weight of the gage-block when the ground is very hard, I have provided lugs 17 on the top of the gage-block, said lugs fitting in slots in weights adapted to be carried on top of said gage-block.

Fig. 4 is a modification of the vertical knife 3, in which the rear end of said knife is provided with outwardly-extending blades 19 and 20, adapted to throw the crown and dirt from the beet the better to enable the pullers to accomplish their purpose.

The operation of my device is as follows: The projection 14 being pivoted to the forward part of a beet-puller, the springs 15 and 16 are connected to the sides of the frame in such position that the vertical knife 3 will strike the center of the beet. Upon forward movement of the topper the disk cutters 11 and 12 will sever the overhanging leaves and throw them away from the beet. The weighted vertical knife 3 will be forced into the beet, and the knives 9 and 10 will cut off the leaves close to the top of the beet. As the topper is moved forward the knives 5 and 6, which run under the ground, will sever the crown of the beet as low as they are permitted to do so by the gage-block.

Having thus described my invention, what I claim as novel, and desire to secure by Letters Patent, is—

1. In a beet-topper, a weighted gage member and a topping-knife mounted upon a vertical knife, said vertical knife being adapted

to be rigidly and adjustably secured to the gage-plate, said plates and knives being capable of free vertical movement.

2. A beet-topper comprising a gage member, a vertical knife carried thereby and adapted to cut into the beet, and knives carried by said vertical knife adapted to top the beet.

3. A beet-topper comprising a gage member, a vertical knife carried thereby, adapted to cut into the beet and approximately horizontal knives adapted to top the beet.

4. A beet-topper comprising a gage member, a vertical knife carried thereby adapted to cut into the upper part of the beet, knives carried by said vertical knife adapted to top the beet, and means located ahead of the toping-knives for removing the leaves.

5. A beet-topper comprising a gage member, a vertical knife adjustably secured thereto adapted to cut into the beet, crown-cut-

ting knives secured to said vertical knife, and leaf-severing knives located ahead of said crown-cutting knives adapted to throw the severed leaves out of the path of said knives. 25

6. A beet-topper comprising a weighted gage member, a vertical knife adjustably secured thereto adapted to cut into the upper part of the beet, crown-cutting knives secured to said vertical knife adjacent its lower edge, leaf-severing knives secured to said gage member ahead of said crown-cutting knife adapted to throw the severed leaves out of the path of said knives and cutting-disks located ahead of said leaf-cutting knives for 30 35 the purposes hereinbefore set forth.

In testimony whereof I affix my signature in presence of two witnesses.

JAMES F. WILLSON.
